UNITED STATES PATENT OFFICE.

JUDSON V. JURY, OF HOUSTON, TEXAS.

FORM FOR CONCRETE CONSTRUCTION.

Application filed June 23, 1924. Serial No. 721,698.

To all whom it may concern:

Be it known that I, JUDSON V. JURY, a citizen of the United States, residing at Houston, in the county of Harris and State of Texas, have invented certain new and useful Improvements in Forms for Concrete Construction, of which the following is a specification.

This invention relates to new and useful improvements in a form for concrete construction.

One object of the invention is to provide a form or mold specially designed for use in erecting the walls of buildings formed of plastic material such as concrete.

Another object of the invention is to provide a type of building form by the use of which the walls of a concrete building may be erected by a practically continuous process, or operation, by elevating the forms when one section of the walls have been poured and have set, and pouring another section, and so on until the walls are completed. The sections thus superimposed one upon the other are united together and form a continuous wall of uniform appearance.

A further feature of the invention resides in the provision of a type of building form whereby a double wall may be erected and tied together in such a manner that the walls may be constructed thinner than customary, thus economizing in the use of material and yet providing sufficient strength.

A still further feature resides in the provision of a form which is very light and consequently easily handled, and yet durable.

With the above and other objects in view, the invention has particular relation to certain novel features of construction, operation, and arrangement of parts, an example of which is given in this specification and illustrated in the accompanying drawings, wherein:

Figure 1 shows an end view of the form partly in section on the line 1—1 of Figure 3, and partly broken away.

Figure 2 shows a side view thereof, partly broken away, and partly in section on the line 2—2 of Figure 3; and

Figure 3 shows a horizontal sectional view on the line 3—3 of Figure 1.

Referring now more particularly to the drawings, wherein like numerals of reference designate similar parts in each of the

figures, the numerals 1, 1 designate the outside mold boards, and the numerals 2, 2, designate the inside mold boards. These may be of any desired width and length, depending on the nature of the building being erected, and may be formed of ordinary wooden boards, or of sheet metal.

The numerals 3 and 4, designate the anchor plates employed, to hold the mold boards 1 and 2 in their proper relation. As indicated in Figure 2 two sets of these plates are employed; for each individual form, one set near each end of the form; but intermediate anchor plates may be employed if desired.

The respective plates 3 and 4, are held spaced apart by suitable washers, as 5, and are secured in fixed relation by means of rivets which pass through said washer and are riveted to said plates.

The plates 3 and 4 have registering slots 6, 7, cut from their lower edges to receive the mold boards 1, 2.

There are thin outside and inside wedges 8, 8, and 9, 9, adapted to fit between the respective plates 3 and 4, of each set of said plates. The edges of these wedges adjacent the respective mold boards 1 and 2 are straight and disposed vertically, and are adapted to fit closely against the corresponding mold boards, and reinforce the same, making angle iron reinforcement unnecessary, and their other edges are tapering, or upwardly flared, and work against the corresponding washers 5, which are disposed to form bearings for the outer, or tapering edges of the wedges.

At the upper ends of the slots 6, 7, the anchor plates 3, 4, are formed with the integral arcuate lugs 10, 11, the former of which is bent around the latter, as illustrated in Figure 2. The lugs 11 form hooks and engage around the cross bolts 12, 12, which are anchored to the upper edges of the respective sets of mold boards 1, 2. These hooks thereby support the said mold boards which are swung therefrom by said bolts 12.

In beginning the work the molds are set in upright position on the foundation, and in practice a number of molds are employed, and set in end to end relation throughout the length of the wall being erected. The wedges 8 and 9 are driven down, wedging

between the bearings 5, and the corresponding mold board until said respective mold boards 1 and 2 are the proper distance apart to give the required thickness to the 5 walls. The plastic concrete is then poured into the forms until they are filled and is thoroughly tamped in place and allowed to set. The plastic material will form around the curved lugs 10, thus leaving the half 10 round notches 13, 13, in the upper edge of each course, as formed.

The anchor plates 3, 4, have upwardly diverging slots 14, 14 and the wedges 8, 9 also have upwardly diverging slots 15, 15. 15 These upper ends of the slots 15 overlap the lower ends of the corresponding slots 14, when the wedges are in lower position. When it is desired to elevate the forms, keys as 16 are driven through said slots, as illustrated in Figure 2, to force them into registering position. This will elevate the wedges and release the anchor plates and the entire form may then be elevated. The forms are elevated until the mold boards do not quite 20 clear the upper edge of the completed section of the wall, and tie rods as 17 are laid transversely with their respective ends resting in opposite notches of the completed 25 wall sections 18, 18, and the molds are then slightly lowered until the inner mold boards 2, 2, rest on said rods, the lower edges of said mold boards having notches 19, 19, to receive the rods, as indicated in Figure 1. The 30 molds are thus supported while another 35 course of the wall is being poured.

The plastic material of this additional course is then poured and will run into and harden in the bottom notches 13, 13, to assist in uniting the superimposed sections together, and the rods 17, 17 also tie the outer 40 and inner walls together. It is to be also understood that vertical reinforcing rods (not shown) will be embedded in each course and the upper ends of these rods will project above said course and be embedded in the course above when it is poured to tie the superimposed sections together in the usual way.

When heavy forms are used a derrick may 50 be erected for a block and tackle (not shown) to be used in the usual way for lifting said forms. The derrick shown consists of the uprights 20, 20, having the crown block 21 for an obvious purpose. The 55 uprights may be provided with the lugs 22, 22, if desired for engagement over the tie rods 17 to support the derrick.

If light forms are used, a lifting bar may be inserted through the bearing slot 23, 60 through the anchor plates, and through this bar the forms may be manually elevated.

The forms are provided with platforms 65 24, 24, arranged on opposite sides of the wall for the use of workmen in pouring the concrete and other work. These platforms

are supported by the horizontal arms 25, 25, which are held in position by means of the supporting rods 26, 26. These arms 25 and 26 have their inner ends formed with eyes through which the securing rivets, connecting the anchor plates 3 and 4, pass, and these respective eyes form spacing washers, heretofore referred to and indicated by numerals 5.

What I claim is:—

1. A mold for walls including spaced mold boards, anchor plates formed with aligned slots to receive the mold boards, said anchor plates being fixed relative to each other, retaining members carried by the anchor plates 80 and adapted to retain the mold boards in position on opposite sides of the wall being formed, and tie rods sustained by the walls and sustaining the mold.

2. A form, or mold, for concrete construction including mold boards spaced apart, anchor plates secured together and formed with aligned slots to receive said mold boards, retaining members associated with said plates and adapted to bear against the outer sides of the respective mold boards, and tie rods adapted to sustain the mold in relation to the construction being molded.

3. A form or mold for concrete construction including mold boards spaced apart, anchor plates secured together and formed with aligned slots to receive said mold boards, retaining members adapted to bear against the outer sides of the respective mold boards, releasing means for releasing the retaining members from the work being constructed, and tie rods for supporting said form relative to the work retaining members from said mold boards.

4. A form for concrete construction including spaced mold boards, anchor plates fixed in spaced relation and formed with registering slots adapted to receive said mold boards, retaining members between said anchor plates and adapted to bear against the outer sides of the mold boards, and tie rods sustained by the construction and sustaining the form.

5. A form for concrete construction including spaced mold boards, anchor plates fixed in spaced relation and formed with registering slots adapted to receive said mold boards, retaining members between said anchor plates and adapted to bear against the outer sides of the mold boards, releasing means adapted to release the retaining members to thereby release said mold boards, and tie rods for sustaining the form relative to the work.

6. A form or mold for concrete construction including spaced mold boards, anchor plates secured in fixed relation and formed with slots to receive said mold boards, means sustaining the mold boards in suspended position from said anchor plates, bearing

members carried by said anchor plates, retaining members between said bearing members and the respective mold boards and bearing against the outer sides of said respective mold boards.

7. A form or mold for concrete construction including spaced mold boards, anchor plates secured in fixed relation and formed with slots to receive said mold boards, means 10 sustaining the mold boards in suspended position from said anchor plates, bearing members carried by said anchor plates, retaining members between said bearing members and the respective mold boards and bearing against the outer sides of said 15 respective mold boards, and means for releasing said retaining members to permit the release of the mold boards from the molded work.

20 8. A form or mold for concrete construction including spaced mold boards, an anchor formed with a slot to receive said mold boards, a connecting member, connecting the upper edges of said mold boards, means carried by the anchor and engaging with said connecting member through which said mold boards are suspended from the anchor, a projection extending into said slot below the upper margin of the mold boards, bearing 25 members carried by the anchor, retaining members adapted to be inserted between the bearings and the outer sides of the respective mold boards and to bear against the latter throughout their width.

30 9. A form or mold for concrete construction including spaced mold boards, an anchor formed with a slot to receive said mold boards, a connecting member, connecting the upper edges of said mold boards, means carried by the anchor and engaging with said connecting member through which said mold boards are suspended from the anchor, a projection extending into said 35 slot below the upper margin of the mold boards, bearing members carried by the anchor, retaining member adapted to be inserted between the bearings and the outer sides of the respective mold boards and to bear against the latter throughout their width, and means for releasing said bearing 40 members for said mold boards.

45 10. A form or mold for concrete construction including two pair of mold boards, the mold boards of each pair being spaced apart, an anchor formed with a pair of slots to receive the respective pair of mold 50 boards, retaining members associated with the anchor and adapted to bear against the outside of the mold boards of the respective

pair, and tie rods adapted to sustain the 60 mold in relation to the construction.

11. A form or mold for concrete construction including mold boards spaced apart, anchor plates secured in fixed relation to each other, and provided with aligned slots 65 to receive said mold boards, lugs formed on said respective plates at the upper ends of said slots, one of said lugs forming a supporting hook and the other forming a projecting mold, means attached to said mold 70 boards, and engaged by said hook and forming a support for said mold boards, wedge shaped retaining members fitted between said anchor plates, each having one edge bearing against the outside of the corresponding mold board, bearings carried by the anchor plates against which the other edges of the retaining members bear, and means for releasing said retaining members 75 from said mold boards.

80 12. A form for concrete construction including spaced mold boards, an anchor formed with a slot adapted to receive said mold boards, retaining members carried by the anchor and adapted to bear against the outer sides of the mold boards, rods supported by the construction and supporting the form and a supporting platform connected to and sustained by said form.

85 13. A form or mold for concrete construction including mold boards spaced apart, anchor plates secured together and formed with aligned slots to receive said mold boards, means for sustaining the mold boards from the anchor plates, retaining means adapted to bear against the outer sides of the respective mold boards, tie rods for supporting the mold boards relative to the construction and a supporting platform on each side of the form, said platforms being 90 connected to and sustained by said anchor plates.

95 14. A form for constructing concrete walls including mold boards spaced apart, anchor plates formed with slots to receive said mold boards, retaining means adapted to bear against the outer sides of the respective mold boards, means adapted to release said mold boards from the wall being constructed and means adapted to hold the mold boards in suspended relation to said anchor plates.

100 In testimony whereof I have signed my name to this specification in the presence of two subscribing witnesses.
